CLAIM

The ornamental design for a hooded garment with integrated light sources, as shown and described.

DESCRIPTION

FIG. 1 is a top front perspective view of a hooded garment with integrated light sources showing my new design;

FIG. 2 is a bottom front perspective view thereof;

FIG. 3 is a top rear perspective view thereof;

FIG. 4 is a bottom rear perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a right elevational view thereof;

(Continued)

FIG. 10 is a left elevational view thereof; and,
FIG. 11 is a vertical cross-sectional view taken along line
11-11 in FIG. 10.
